UNITED STATES PATENT OFFICE

KARL ULRICH, OF ZWEIBRÜCKEN, GERMANY.

DEVICE FOR DAMPING THE AIR IN CLOSED ROOMS.

971,227.

Specification of Letters Patent. Patented Sept. 27, 19

Application filed June 28, 1909. Serial No. 502,895.

To all whom it may concern:

Be it known that I, KARL ULRICH, a subject of the German Emperor, and resident of No. 21 Fabrikstrasse, Zweibrücken, Pfalz, 5 Germany, have invented certain new and useful Improvements in Devices for Damping the Air in Closed Rooms, of which the following is a specification.

In spinning and weaving-mills and other 10 textile factories in general, and in particular in silk-spinning and silk-weaving mills; also in tobacco-factories, the work is made difficult during the dry time of the year by the fact that in consequence of the dry air the 15 fibrous material and the tobacco-leaves become very easily brittle and are apt to crumble, whereby there is not only formed dust, which the workers have to inhale, but a great deal of material also is lost, as well 20 as time, as in silk-spinning and silk-weaving mills and in textile factories in general the broken threads require to be tied together again. By this work an extraordinary great deal of time is lost, so that on such days the 25 output is often reduced to about two thirds. But also in hospitals, especially in those for pulmonic patients, where a damp atmosphere is a necessary condition for a favorable course of the disease the dryness of the 30 air is very unpleasantly felt. It has frequently been attempted to remove this drawback by finely spraying water and mixing it with the air, to form a kind of fog, or by letting steam pass out through holes in a steam- 35 conduit. Both processes have their drawbacks. The water-fog is deposited in spinning and weaving-mills on the metal parts, so that they become rusty, which is in silk-spinning and silk-weaving mills particularly 40 dangerous. The same applies to the simple distribution of steam, especially as at the opening through which the steam passes out there takes place a condensation and the formation of drops which, when they fall 45 down, fall partly on the machinery and partly on the silk and damage the same. Moreover by the formation of fog or the ordinary distribution of steam, it is not possible to moisten the air in the whole room 50 uniformly if special distributing-ventilators are not used. These cause drafts which are likewise to be avoided in silk-spinning and weaving-mills as well as in hospitals.

The object of the present invention is to 55 effect in all the above-mentioned cases a uniform moistening of the air and in such a

manner that no injurious deposits or products of condensation are formed and no further movement of the air is necessary. According to the same steam is likewise introduced into the respective work-room or hospital-room, but the steam, before it passes into the room, is freed of the water contained in it by a special spray-nozzle and the product of the condensation formed in the latter is caused to pass into a proportionately narrow conduit, running along the steam-conduit, below or above the same, so that the air cannot be polluted by the product of the condensation. In order to prevent a detrimental cooling of the steam-conduit and of the spray-nozzles as well as a non-intended giving-off of heat through the same, they are covered in the well known manner by a mass which prevents this. But in order to avoid the formation of a vacuum in the conduit and thereby a passing over of the steam from the spray-nozzle into the latter, the conduit conveying the product of condensation is covered with a similar mass, so that the steam entering the said conduit can exert a certain counter-pressure upon the steam in the spray-nozzles.

The drawing, wherein similar letters refer to similar parts throughout the several views, illustrates in Figure 1 a part of the steam-conduit *a* and of the conduit *b* for the condensed steam with the spray-nozzles *c* in a front view and in Fig. 2 in a cross-section. The conduit for the condensed steam is in this case arranged below the steam-conduit. In Figs. 3 and 4 are shown two other forms of the arrangement of the conduits for the steam and condensed steam in a cross-section and in Fig. 3 the conduit for the condensed steam is arranged by the side of the steam-conduit, while in the arrangement according to Fig. 4 it surrounds the steam-conduit concentrically. Fig. 5 shows a spray-nozzle in a longitudinal section, while Figs. 6, 7 and 8 show a cross-section of the same on the lines A—B, C—D and E—F.

It is advantageous to connect the two conduits *a* and *b* so with each other that they form a rigid whole, as otherwise the connections with the spray-nozzle would too easily be made untight by the mutual movements, and drops would be formed as a result. In the form of construction according to Figs. 1 to 3 both conduits, *a* and *b*, are in the first place supported by props *d*, and after they have been covered with the coating-mass *e*

They are united with each other by bows *f* placed over the latter. In the form of construction according to Fig. 4 the conduit *b* for the condensed steam surrounding the steam-conduit is only so large that there remains between the two a narrow concentric interspace *g* for receiving the steam to be condensed. The conduit *a* can be supported in the conduit *b* by ribs or, as shown in Fig. 19, by supporting bolts or screws *h*, inserted into the conduit *b*. This arrangement, it is true, makes it necessary to make the conduit *b* a little larger, but the conduit *a* is thereby protected the better against losses of heat, as 15 it is in the first place surrounded by the condensation-room and further by the mass *e* for preventing the loss of heat.

The spray-nozzle *c*, which stands in communication by a tube *i* which can be shut off, 20 with the steam-conduit, and by a thin and partly spiral tube *k* with the condensation-conduit, is preferably made of a casing formed by two double cones, into one of whose ends opens the connecting-conduit, 25 while at the other end there passes out the steam spraying-tube *l*. The inside of the casing of the nozzle is divided by partition-walls *m*, *m*¹ and a capsule-shaped partition-wall *m*² into four spaces *n*, *n*¹, *n*² and *n*³. 30 The tube *i* projects into the room *n*¹ and is open in front as well as provided at the top with an outlet opening *o*. The partition wall *m*¹ in front of the mouth of this tube *i* is fitted out, near the border, with steam-outlets *r*. The tube *l*, which lets the steam pass out of the spray-nozzle, projects rather far into the room *n*³ of the nozzle, and is surrounded by the capsule-shaped partition-wall *m*², which is provided on its circumference with steam-outlets *s*. From the lower part of the cap there branches off a condensing-tube *u* opening into the space *n*¹ of the nozzle. The partition wall *m* itself is provided at the bottom with an opening *x* 45 for letting through the waste-water. If the nozzles are arranged under an angle of about 45°, the tube *k* for letting off the waste-water is inserted into the casing of the nozzle close to the partition-wall *m*. But if the spray-nozzles are arranged vertically, the tube *k* 50 must open into the casing of the nozzle close to *y*. The course which the steam takes in the inside of the nozzle is the following: Coming out of the tube *i* it passes into the room *n*¹, rebounds on the one side on the partition-wall *m*¹ and, on the other, if it passes out through the opening *o*, it rebounds on the upper wall of the casing of the nozzle, 55 is distributed in the room, enters through the openings *r* of the partition wall into the room *n*² of the nozzle and from here through the openings *s* into the space *n*³ of the nozzle and then into the spray-tube *l*, through which it leaves the nozzle. The particles of water separated in the different rooms collect

at the lowest place of the nozzle and enter into the tube *k* through which they are conducted into the tube for letting off the waste-water. In consequence of the fact that the spray-tube freely projects into the last room 70 of the nozzle water carried along the wall of the nozzle by the rush of the steam cannot get to the outlet-tube, so that it can be fully relied on that only steam freed of water can pass out. 75

What I claim as my invention and desire to secure by United States Letters Patent is:—

1. A device of the class described comprising a steam supply chamber, a spray nozzle communicating therewith, perforated partition walls within said nozzles forming a plurality of steam chambers, a spray tube projecting into the final steam receiving chamber and constructed and arranged 80 to convey the steam, free from the particles of condensation, into the atmosphere.

2. A device of the character described comprising a spray-nozzle having a plurality of communicating steam chambers, 90 said chambers having outlet ports whereby the water of condensation formed in said chambers will readily flow therefrom.

3. In a device of the class described, the combination with a steam supply chamber, 95 of a plurality of nozzles communicating therewith, a common conduit adjacent to and outside of said steam chamber, and tubes communicating with the lower end of said nozzle and with said conduit for conducting the water of condensation formed in said nozzles into the common conduit. 100

4. In a device of the character described, comprising a steam chamber, spray nozzles connected therewith, and means constructed 105 and arranged in said nozzles for freeing the steam of particles of condensation.

5. In a device of the character described, comprising a steam chamber, spray nozzles connected therewith, and means constructed 110 and arranged in said nozzles for freeing the steam of particles of condensation, and pipes in communication with said spray nozzles for removing the water of condensation therefrom. 115

6. In a device of the character described, the combination with a steam supply chamber, of diverging nozzles, and tubular means connecting said nozzles to the supply chamber. 120

7. In a device of the character described, the combination of a steam supply chamber, spray nozzles communicating therewith, a plurality of chambers formed in said nozzles, each chamber having inlet and outlet ports, 125 the inlet ports positioned at substantially right angles to the outlet ports.

8. In a device of the class described, the combination of a steam supply chamber, spray nozzles constructed and arranged to 130

separate the particles of condensation from the steam, a conduit for receiving the water of condensation, and means for conveying the water of condensation from the nozzles to said conduit.

9. In a device of the character described, the combination with a steam supply chamber, of diverging nozzles, and tubular means connecting said nozzles to the supply chamber, and valves positioned in the tubular means for controlling the flow of steam from the chamber to the nozzles.

10. In a device of the class described, the combination with a steam supply chamber, of a plurality of discharging nozzles, rigid tubes connecting the supply chamber with the nozzles and a conduit to receive the water of condensation, and pipes connecting the nozzles and said conduit.

11. In a device for moistening air, the combination with a steam supply chamber, of nozzle communicating therewith, a conduit for receiving the water of condensation, and a spiral tube connecting said conduit with the nozzle.

12. In a device for moistening air, the combination with a fluid supply chamber, a discharge nozzle, a conduit surrounding said supply chamber, but not in communication therewith, and tubular means passing through said conduit and into the supply chamber, so that the nozzle will communicate with the supply chamber.

13. In a device for moistening air, the combination with a fluid supply chamber, a discharge nozzle, a conduit surrounding said supply chamber, but not in communication therewith, tubular means passing through said conduit and into the supply chamber, so that the nozzle will communicate with the supply chamber, and a separate rigid tube for connecting the nozzle with the conduit.

14. In a device for moistening air, the combination with a fluid supply chamber, a discharge nozzle, a conduit surrounding said supply chamber, but not in communication therewith, tubular means passing through said conduit and into the supply chamber, so that the nozzle will communicate with the supply chamber, and separate connecting means between the nozzle and conduit.

15. In a device of the character described, the combination of a steam supply chamber with a nozzle communicating therewith, a plurality of compartments formed in said nozzle, a pipe secured in said nozzle and projecting beyond the discharge end thereof.

16. In a device of the character described, the combination with a steam supply chamber, of a discharge nozzle in communication therewith, the interior thereof divided into a plurality of communicating chambers, one of said chambers adapted to receive the water of condensation from the other chambers.

17. In a device of the character described, the combination with a steam supply chamber, of a spray nozzle communicating therewith, a discharge tube secured in one end of said nozzle and projecting beyond the discharge end thereof.

18. In a device for moistening air, a spray nozzle, the interior thereof divided into a plurality of communicating chambers, one of said chambers communicating with the atmosphere, and means for removing water of condensation from said last-named chamber.

The foregoing specification signed at Neustadt a. Hardt this 14th day of June, 1909.

KARL ULRICH.
